STOKER MECHANISM

Edwin Archer Turner, New York, N. Y., assignor
to The Standard Stoker Company, Incorporated,
a corporation of Delaware

Original application June 12, 1926, Serial No.
115,623. Divided and this application May 2,
1930, Serial No. 449,098

2 Claims. (Cl. 110—101)

This is a division of my application, Serial Number 115,623, filed June 12, 1926, Patent No. 1,779,570, granted October 28, 1930.

This invention relates to stoker mechanism 5 and more particularly to fuel distributors and the like.

The principal object of the invention is the provision of a novel distributor tube having a curved tubular extension formed therewith.

10 Another object of the invention is the provision of a novel distributor member that is cheap to manufacture, easily assembled on the stoker, efficient in operation, strong and durable and that reduces the number of parts thereby 15 eliminating joints that can work loose and cause trouble.

Other and further objects and advantages will readily appear to those skilled in the art from the following drawings, in which

20 Fig. 1 is a rear view of a locomotive, showing the invention in position thereon;

Fig. 2 is a vertical section of the rear portion of a locomotive, showing one form of the invention in position thereon, with parts in section 25 and parts broken away; and

Fig. 3 is a section on line 3—3 of Fig. 2.

On the drawings, the reference character 10 designates the backhead of a conventional locomotive, 11 the firebox thereof, and 12 the fire-door opening. The stoker is designated generally by the reference character 13 and comprises the conveyer 9 for transferring the fuel from a source of supply, as the tender, to the locomotive, a pair of divergent fuel conduits or elevators 35 14 and an adjustable divider 8 for dividing the stream of fuel from the conveyer in proper proportions for the two elevators.

The conveyer and elevators are preferably of the screw type and are adapted to be operated 40 through suitable gearing from a motor 15 in the usual manner. Since the details of the driving mechanism and the screw conveyer constitute no part of the present invention, it is not thought necessary to further describe or illustrate the 45 same.

In the form of the device shown in Figs. 1 and 2 the upper or terminal portion of each elevator conduit is in the form of an elbow or curved tubular portion 16, the front end of which constitutes a distributor member 20 extending through an opening 17 in the backhead 10 for distributing fuel over the grates of the firebox. Each elbow is provided with an opening 25 through which access may be had to the interior of the elbow. A closure 26 is provided for

the opening 25. It is preferably though not necessarily hinged at its upper end as at 27 and a latch 28 holds the same in closed position.

It is desirable that means be provided for detachably connecting the distributor members 5 to the elevator casings whereby the distributor member may be removed for replacement or repairs. As shown, the elbows 16 are detachably connected to the upper ends of the elevator casings by means of bolts or other fastening elements extending through the abutting flanges 18.

The elevators 14 comprise elevator screws 21, which for convenience in removing the elbows 16, terminate adjacent to the upper ends of the 15 elevator casings. The elbow is provided with a curved bore the curved portion of which is preferably dome-shaped, whereby fuel forced upwardly by the screw elevator will be directed onto the distributor in front of the steam nozzle 22. 20 The nozzle 22 is preferably provided with a plurality of steam jets which are supplied by steam from the pipes 30 for projecting the fuel into the firebox.

The front end of the distributor member is 25 provided with a baffle 23 and forwardly and laterally extending channels 24 as is well understood in the art.

The front end of the distributor member 20 extends into the firebox and consequently is subjected to the intense heat of the burning fuel during the operation of the locomotive. In order to prevent the distributor member from becoming damaged or incapacitated by the heat of combustion, suitable means are provided for 35 cooling the distributor member.

In the form of the device selected to illustrate one manner of accomplishing this function, the distributor member is cooled by circulating a fluid therethrough. The distributor member is 40 cored as at 31 to form a water jacket through which water is adapted to be circulated. Preferably the water is forced through the jacket by the water pump, entering the jacket through the pipe 29 at the rear lower portion of the distributor 45 member and passing from the same through the pipe 32 into the boiler of the locomotive above the fire door opening.

The pipe 29 is connected to the backhead 10 through a short length of pipe 33 having the valve 50 34 therein. The pipe 32 is provided with a check valve 36 for preventing the return of the water and steam from the boiler. If desired the pipe 29 may be provided with a valve 35 whereby the pipe 29 may be closed below the branch pipe 33 55

and by opening the valve 34 water from the boiler will circulate through the water jacket of the distributor tube.

The water jacket at the rear portion of the distributor member may be provided with a horizontal partition 37 which will cause the water entering below the partition to flow to the front of the water jacket in passing through the distributor tube.

- 10 10 In the operation of the device, water is forced by the pump through the pipe 29 or flows by gravity through the pipe 33 into the pipe 29 and thence it passes into the rear lower portion of the water jacket of the distributor tube, thence 15 forwardly and upwardly, and then rearwardly and out through the pipe 32 and into the boiler through the backhead of the locomotive.

I claim:

1. In combination, a firebox having a wall with an opening therein, a stoker fuel conduit including a casing mounted more nearly vertical than horizontal externally of the firebox and being approximately straight along its medial longitudinal center line, a terminal portion comprising an elbow, said elbow forming a continuation of said casing and having its upper wall longitudinally curved towards the opening in said firebox wall, said terminal portion also comprising a fuel distributing member in the opening in said firebox 20 wall having a fuel receiving surface extending forwardly from the lower forward edge of said elbow, means at the rear of said fuel distributing member adjacent the lower forward edge of said elbow for projecting fuel across said fuel receiving surface into the firebox, a conveyer screw mounted in said fuel conduit and terminating therein at its upper end below the lower edge of the curving upper wall of said elbow and below the lower forward edge of said elbow a distance 25 sufficient to permit a core of fuel to form in and

fill a portion of said conduit above said screw, said curving upper wall having a radius of curvature not less than half the diameter of said casing whereby the core of fuel advanced by said screw will be directed forwardly through said elbow onto the fuel receiving surface of said distributing member immediately in front of said fuel projecting means.

2. In combination, a firebox having a wall with an opening therein, a stoker fuel conduit including a casing mounted more nearly vertical than horizontal externally of the firebox and being approximately straight along its medial longitudinal center line, a terminal portion comprising an elbow, said elbow forming a continuation of said casing and having its upper wall longitudinally curved towards the opening in said firebox wall, said terminal portion also comprising a fuel distributing member in the opening in said firebox wall having a fuel receiving surface 20 extending forwardly from the lower forward edge of said elbow, means at the rear of said fuel distributing member adjacent the lower forward edge of said elbow for projecting fuel across said fuel receiving surface into the firebox, a conveyer screw mounted in said fuel conduit and terminating therein at its upper end below the lower edge of the curving upper wall of said elbow and below the lower forward edge of said elbow a distance sufficient to permit a core of fuel to form 25 in and fill a portion of said conduit above said screw, said curving upper wall having a radius of curvature not less than half the diameter of said casing and extending forward of the fuel projecting means whereby the core of fuel advanced by said screw will be directed forwardly through said elbow onto the fuel receiving surface of said distributing member immediately in front of said fuel projecting means.

E. ARCHER TURNER. 40
